RAZOR STROPPING MEANS

Filed June 14, 1927

Inventor:
Paul Müller

UNITED STATES PATENT OFFICE

PAUL MÜLLER, OF SOLINGEN, GERMANY

RAZOR STROPPING MEANS

Application filed June 14, 1927, Serial No. 198,821, and in Germany May 9, 1927.

This invention refers broadly to improvements in stropping means for razors, surgical knives, corn-blades and the like, and it is particularly adaptable for the stropping and 5 sharpening of knives with reinforced back and but one cutting edge, though it is not restricted to this use and in its broad features may find employment in connection with other kinds of razors or the like, such 10 as razors of the plate-shaped or wafer-shaped type, and it is one of the important objects of the invention to greatly facilitate and accelerate the stropping operation, to save the delicate sharp edge from injury, and to 15 simplify the construction of devices of the class referred to. In view of these and other important objects and advantages means are provided according to this invention to detachably mount the razor blade or the like to 20 be treated in a spring actuated holder, rotatably mounted in a carriage, adapted to be axially reciprocated in parallelism to the stropping surface by gear-and-rack connection or by similar means, and alternatingly 25 rocked in opposite directions in accordance with the reciprocation of the carriage, so that different sides of the blade will become operatively engaged with the stropping surface. In accordance with one particular 30 form of preferred embodiment of the invention the means for the reversing of the shaft of the blade holder mainly comprises a rack bar in the longitudinal direction of the carriage guide, and engaging with a pinion or 35 gear wheel mounted on the carriage and upon the shaft of the blade holder. The coupling of the blade holder with this driving and reversing shaft is preferably effected by a strong spring-actuating split collar. The 40 stropping surface or the like is preferably provided on a suitable resilient insertion piece supported between the carriage guides and preferably adapted to be used on both sides. 45 Among the various advantages of the new device the following may be mentioned in particular. In view of the reversible feeding and operating action being produced by gear wheel action great exactness and reliability of operation is insured, and the blades 50 to be stropped or honed are caused to proper-

ly and most uniformly engage the stropping surface which is thereby likewise protected from being cut, and a most simple, easy and reliable manipulation of the entire device is produced. In view thereof and by means of the novel construction great durability of the apparatus is insured without danger of interruptions during operation even with frequent and heavy usage.

The invention will be more fully described by reference to the accompanying drawing showing by way of exemplification two of the various possible embodiments of the principles of the invention.

In the drawing:—Figure 1 is a top plan view of the total arrangement of the device.—Figure 2 is a side elevation with parts in section.—Figure 3 is a transverse section on the line A—B of Figure 1, and Figure 4 is a transverse section on the line C—D of Figure 1. In Figure 5 a modification is shown representing a two-sides stropping device for the simultaneous treatment of two razor blades in a longitudinal section along the section line E—F of Figure 1.

In accordance with the exemplification of Figures 1—4 the carriage 2 is provided with a handle 1, and is guided on the guide rods 3 and 4 in the longitudinal direction of a supporting frame 5 of sheet metal or other suitable material. With the rack bar 4 which constitutes one of the guide rods a pinion or gear wheel 6 is engaged which is rotatably disposed on the carriage 2 and which during the reciprocation of the carriage 2 is adapted to rotate a gear wheel 8 on the transverse shaft 7 in one or the other direction, so as to rotate said shaft 7 in the corresponding direction. Upon this shaft 7 disposed at the front portion of the carriage the holder 9 for the spring-acting interchangeable mounting of the blade to be treated is rotatably mounted, and is for instance, frictionally coupled to the shaft 7 by means of a collar 12 preferably formed from suitably bent flat springs. By the action of this frictional coupling and of the gearing elements 4, 6, 8, 7 the blade holder 9 is turned into the opposite stropping or grinding position upon reversing the direction of movement of the

carriage 2, while upon continuing to move the carriage in either of these directions the blade is closely forced against the stropping surface 13 without any liability of injuring the cutting edge thereof.

5 In accordance with the modification shown in Figures 1 to 4 this stropping surface is provided on one side of a readily removable tensioning support 14 mounted in the supporting frame 5 and on the other side of which an additional and preferably differently arranged stropping surface 15 may be secured, in order to allow for instance of a preliminary and supplemental sharpening of the blades to be 10 treated by merely reversing the tensional 14 in the frame 5.

15 In the modification according to Figure 5 which provides for the employment of both sides of the device according to this invention, the guide rod 4 for the double-carriage 2 may be toothed on the upper and lower sides, and by the operation of the handle 1 the blades 10 are stropped or honed by being moved along the treating surfaces 13 and 15 20 respectively of the inserted support 14, holding and coupling means being provided upon the upper and lower sides of the stropping means 13, 15 with corresponding coupling means and gear wheels by means of which the 25 blades and their holders are reversed upon the corresponding reciprocation of the carriage.

30 The carriage movement is limited in its terminal positions on the frame 5 by suitable means, such as for instance by impinging against the front walls of the frame or by other stropping means. While the arrangement shown by way of exemplification on the 35 accompanying drawing has been found useful for carrying out the objects of my invention, it should be understood that other modifications are possible, and I therefore do not desire to be limited in the scope of my protection except as outlined in the appended 40 claim.

45 I claim:—

50 A stropping and blade-treating device, comprising, in combination, a longitudinal frame and two longitudinal guide rods, of which one is designed as a rack; sleeves 55 adapted to be shifted along said rods and a grip forming frame connected with said sleeves; a transverse shaft supported by said latter frame just over the said sleeves, a pinion affixed to one end of said shaft, and a transmission cog-wheel carried by said grip-forming frame and meshing with said rack, as well as with said pinion; a blade-holder 60 attached to the said shaft and comprising a sleeve enclosing this shaft, and two ledges projecting forth from these sleeves and adapted to receive a blade between them; and a stropping member located in said frame between the said rods.
